US00D979326S

(12) **United States Design Patent** (10) **Patent No.:** **US D979,326 S**
(45) **Date of Patent:** **** Feb. 28, 2023**

(54) **ROTISSERIE BASKET**

(71) Applicant: **Weber-Stephen Products LLC**,
Palatine, IL (US)

(72) Inventors: **Christian Hyde**, Schaumburg, IL (US);
Daniel Ramirez, Des Plaines, IL (US);
Robert Farmer, Naperville, IL (US);
Romualdo Sonny Siazon, Woodstock,
IL (US); **Brian C. Donnelly**,
Naperville, IL (US); **Cassandra A. S.
McVey**, Palatine, IL (US); **Shannon
Ella Cerny**, Aurora, IL (US); **Michelle
Stohl**, Glenview, IL (US)

(73) Assignee: **WEBER-STEPHEN PRODUCTS
LLC**, Palatine, IL (US)

(**) Term: **15 Years**

(21) Appl. No.: **29/788,854**

(22) Filed: **Aug. 5, 2021**

(51) LOC (14) Cl. **07-02**

(52) U.S. Cl.
USPC **D7/409**

(58) **Field of Classification Search**

(57) **CLAIM**

The ornamental design for a “rotisserie basket”, as shown
and described.

DESCRIPTION

FIG. 1 is a perspective view of a rotisserie basket.

FIG. 2 is a front view of the rotisserie basket of FIG. 1.

FIG. 3 is a rear view of the rotisserie basket of FIG. 1.

FIG. 4 is a right side view of the rotisserie basket of FIG. 1.

FIG. 5 is a left side view of the rotisserie basket of FIG. 1.

FIG. 6 is a top view of the rotisserie basket of FIG. 1; and,

FIG. 7 is a bottom view of the rotisserie basket of FIG. 1.
The features shown in broken lines form no part of the
claimed design.

The lighter solid lines denote surfaces and contours. Line

shading is not surface ornamentation.

1 Claim, 7 Drawing Sheets
